UNITED STATES PATENT OFFICE.

AMOS BENJAMIN HALLER, OF BRUNSWICK, MARYLAND.

SIGNAL ATTACHMENT FOR HEADLIGHTS.

SPECIFICATION forming part of Letters Patent No. 680,773, dated August 20, 1901.

Application filed May 10, 1901. Serial No. 59,620. (No model.)

To all whom it may concern:

Be it known that I, AMOS BENJAMIN HALLER, a citizen of the United States, residing at Brunswick, in the county of Frederick and 5 State of Maryland, have invented new and useful Improvements in Signal Attachments for Headlights, of which the following is a specification.

My invention has relation to classification-lights; and it consists in the novel construction and arrangement of its parts, as herein-after described.

The object of the invention is to provide a device adapted to transmit light from one 15 source to one or more receptacles or signal-boxes known as "markers" and at the markers to illuminate signals of different colors.

The device is especially designed to be used on a locomotive-engine and as a rear-end signal for trains; but it may also be used 20 to transmit light from a single source to distant points for many purposes, such as illuminating signs and transparencies and for reading and illuminating in general, the advantage of the light so transmitted being 25 that it is devoid of heat.

When used on locomotives and trains, the device is intended to take the place of the ordinary signal-lamps now generally used. 30 These lamps use coal-oil and frequently smoke and go out. Also the glass becomes dampened with oil, which collects the dust and smoke, preventing the bright display of light, which sometimes misleads and causes 35 accidents.

When applied to a locomotive, the device can be operated by the engineer from the cab, who can manipulate the parts so as to display signals of various colors or cut the 40 light off altogether. There being no oil-light in the markers, there is nothing to collect foreign matter and no smoke to affect the signals. Consequently the device is reliable.

In the accompanying drawings, Figure 1 is 45 a front elevation of an engine, showing the signal-light applied thereto. Fig. 2 is a side elevation of Fig. 1, partly in section. Fig. 3 is a top plan view of the markers and connections. Fig. 4 is a perspective view of the 50 end of the reflector-shaft and its bearings. Fig. 5 is a vertical sectional view of the marker. Fig. 6 is a horizontal sectional view

of the marker. Fig. 7 is an elevation of the upper tube ends, showing the reflector attached thereto. Fig. 8 is a side elevation of 55 Fig. 7, and Fig. 9 is a detail view showing the means for attaching the tube-sections together.

The signal, as shown in the accompanying drawings, is especially adapted to be used in 60 connection with the headlight of a locomotive. The small reflector 1 is attached to the reflector-shaft 2, said shaft being journaled in the uprights 3 3. The reflector 1 is located within the casing of the headlight 4, 65 the reflector 1 when in use being in such a position as not to interfere with the light from the lamp. One end of the shaft 2 passes laterally through the side of the headlight-casing and is provided with an opening adapted 70 to receive a pin 5, said pin also passing through a recess in the bearing 6, thus preventing the shaft 2 from rotating or wabbling.

The uprights 3 3 are attached at their lower 75 ends to the chute 7, and said chute in turn is connected with the upper ends of the tubes 8 8. A marker 9 is located at each side of the boiler-front, the lower ends of the tubes 8 8 connecting with said markers in a manner as shown in Fig. 1. Each marker 9 is provided with two light-openings 10 10, and in the top of each marker is journaled a shaft 11. The glass annulus 12 is fixed to the top of the marker, and the glass annulus 13 is 85 fixed to the shaft 11. These annuli come together and form a bearing and support for the shaft 11. The hood 14 covers and protects the said bearings. To the lower end of the shaft 11 the frame 15 is attached, the 90 said frame being located in the interior of the marker 9. The top of the frame is provided with a light-cut-off 16, (see Fig. 6,) said light-cut-off 16 being adapted at intervals to pass under the light-inlet opening 17 and cut off 95 the light to the marker. The frame 15 is also provided with grooves 18 18, adapted to receive the colored glass 19. The glass 19 is at intervals adapted to be thrown behind the light-opening 10 10, and thus the color of the 100 light from the marker is changed.

The top of each marker is provided with doors 20, through which the glass 19 may be removed from the frame 15 and new ones put

in in case of breakage. The upper end of the shaft 11 is provided with a lever 21. (See Fig. 3.) The upper end of the lever of the opposite marker is provided with a bell-
5 crank lever 22. The rod 23 connects the end of the lever 21 with one end of the bell-crank lever 22. The rod 24 connects the other end of the bell-crank lever 22 with the cab of the engine.

10 In operation the rays of light from the head-lamp 4 are thrown by the reflector 1 down into the chute 7 through the tubes 8 8 into the markers 9 9. The inner surface of the chute 7, the tubes 8 8, and the markers 9 9 are 15 highly polished. By manipulating the rod 24 and its connections the engineer can show either a green or white light in the markers or he can cut the light off altogether.

15 In case the headlight 4 should go out or 20 for any other reason be rendered incapable the engineer can light the oil-lamps 25 25 in the markers and display the different colors by manipulating the rod 24, as above described.

25 As a means for holding the ends of the tubes 8 8 in place the lower ends of the bifurcations of the chute 7 are provided with spring-strips 26, having at their lower ends openings 27, said openings being adapted to receive 30 projecting pins on the upper ends of the tubes 8 8. The rings 28 are then slipped down over the strips 26, and the jostling of engine will have a tendency to cause the said rings 28 to descend and make the strips 26 35 more firmly hold the pins at the upper ends of the tubes 8 8. The same kind of connection is made at the lower ends of the tubes 8 8, as indicated in Fig. 1, where they enter the light-inlet 17 of the markers. By providing 40 a glass bearing between the shaft 11 and the top of the marker 9 the said bearing will not have to be oiled, and is of a durable nature, simple in its construction, and reduces the friction and wear to a minimum.

45 In applying the apparatus to the rear-end lights of a train the last light in the last coach is used, and from this light the rays are sent to the markers at the rear end of the coach, thus making one light do the work of three, 50 which avoids the necessity of using oil in the markers and doing away with the disadvantages of the accumulation of dirt and smoke caused by the use of oil, as above described.

55 In order to spread the light more generally, the lamp 25, located in the marker 9, is provided with a highly-polished flange 29. The light falling on the flange is reflected through the light-openings 10 and the glass interposed behind the same.

60 Having described my invention, what I claim as new, and desire to secure by Letters Patent, is—

1. In combination with a light, a signal, consisting of a marker, having several different-colored transparencies permanently attached thereto, and a means for operating the transparencies, a tube connecting the marker with

the casing of the light, a reflector located in the light-casing and adapted to send the rays of light through the tube into the marker. 70

2. In combination with a light, a signal, consisting of a plurality of markers, each having several different-colored transparencies, and a means for changing the transparencies of the markers simultaneously, a tube 75 leading to each marker and connected with the casing of the light, a reflector located in the light-casing, and adapted to send the rays of light through the tubes into the markers. 80

3. In combination with a light, a signal, consisting of a marker having several different-colored transparencies, a tube connecting the marker with the casing of the light, a reflector located in the light-casing and adapted to 85 send the rays of light through the tube into the marker, and a means for changing the transparencies in the markers and a means for cutting off the light from the markers.

4. In combination with a light, a signal, consisting of a plurality of markers each having several different-colored transparencies, a tube leading to each marker, and connecting with the casing of the light, a reflector located in the light-casing and adapted to send 95 the rays of light through the tubes into the marker, a connection connecting the different-colored transparencies of the markers, and a connection extending therefrom and adapted to operate the transparencies in the markers. 100

5. In combination with a light, a signal consisting of a plurality of markers, each having several different-colored transparencies, a tube leading to each marker and connecting with the casing of the light, a reflector located in the light-casing and adapted to send the rays of light through the tubes into the markers and a means for changing the transparencies of the markers simultaneously, and a means for cutting the light off from 105 the markers simultaneously. 110

6. In a device of the character as described, a marker consisting of a casing, having light-openings, a shaft passing through the top of the casing, glass bearings located on top of the casing and receiving and supporting the shaft, a frame supported by the shaft and being located within the casing, said frame carrying transparencies and a means for rotating said shaft. 120

7. In a device of the character as described, means for sending the rays of light from a source to a marker, consisting of a tube connecting the light-casing with the marker, a reflector mounted upon a shaft within the 125 light-casing, said shaft extending to one side through the casing and a means located on the outer side of the casing and adapted to prevent the shaft and the reflector from rotating.

8. In combination with a light, a signal, consisting of a plurality of markers, a shaft journaled in the top of each marker, a frame fixed to each shaft and located within the 130

marker, said frames carrying transparencies, and light cut-offs, a tube connecting each marker with the light-casing a reflector located within the light-casing and adapted to 5 send the rays of light through the tubes into the markers, a lever attached to the upper end of one of the shafts, a bell-crank lever attached to the upper end of the other shaft, a rod connecting said lever with one of the ends of the bell-crank lever, a rod connecting the other end of the bell-crank lever and extending to a distant point.

In testimony whereof I affix my signature in presence of two witnesses.

AMOS BENJAMIN HALLER.
